MEASURED SERVICE TELEPHONE SYSTEM

Original Filed July 3, 1922 2 Sheets-Sheet 2

UNITED STATES PATENT OFFICE.

JOHN WICKS, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed July 3, 1922. Serial No. 572,658.

The present invention relates in general to measured service telephone systems, and more particularly to automatic measured service systems in which a type of paystation apparatus is provided at each subscriber's station requiring the deposit of a coin for each connection.

The general object of the invention is to provide improved circuit arrangements for the coin controlling apparatus, which in this case is a repeater individual to each of the paystation subscribers' lines.

Another object of the invention is to so arrange the circuits of this repeater, that the toll operator may collect or refund coins deposited in the paystation mechanism to pay for an established toll connection, without having any special equipment, such as the usual toll service trunks and separate trains of switches.

The above and other objects of the invention will be explained hereinafter, reference being had to the accompanying drawings.

Referring now to the drawings, comprising Figs. 1 and 2, there is shown sufficient of the apparatus to enable the invention to be readily explained and understood. This comprises the individual line repeater D, the line switch C, a first selector E, and a connector H, these switches being used to complete a connection from the line of the substation A to the line of the substation A'.

Referring now more particularly to Fig. 1, the substation A is of the automatic type, having the usual talking instrumentalities and an impulse sender S. Being a measured service substation telephone, there is also provided a well-known type of coin collecting mechanism, which may be of the same structure as that shown and described in the United States patent to Forsberg, No. 1,043,219, granted November 5, 1912.

The line conductors 11 and 12 extend from the subscriber's substation to the exchange, and at the latter point, through the repeater D to the individual line or trunk selecting switch C. The repeater D controls the coin collecting and refunding operations of the paystation mechanism in a manner which will appear fully hereinafter.

The line switch C is of the usual rotary type, whose wipers have no normal position. This line switch in common with a plurality of others has access to first selector switches, such as the selector E, Fig. 2.

The selector E is of the usual Strowger vertical and rotary type. The circuits of this switch are well-known and have only been partly shown in the drawings. The selector E has access to trunk lines extending to connector switches, one of these connectors being shown in the drawings at H.

The connector H is a switch of the well-known vertical and rotary type, and is adapted to complete connections to subscribers' lines, one of these being that of the substation A'.

The substation A' is of the usual automatic type and may be similar to the substation A, Fig. 1, however, for convenience the measured service equipment has been omitted. The line of the substation A' terminates at the exchange in the line switch C'.

The line switch C' is similar to the line switch C, Fig. 1, already described.

The relays which are slow to pull up and also slow to release are shown with the copper slugs in black, while the relays with the copper slugs shaded are only slow to release.

While in the drawings only one selector has been shown, it will be understood that the system may be enlarged to any desired size by the insertion of standard selector switches between the selector E and connector H.

Having briefly described the equipment shown in the drawings, its detailed operation will now be explained. For this purpose, it will be assumed that a subscriber at substation A desires to extend a connection to the line of the substation A'. In order to do this the calling subscriber will remove his receiver, deposit a coin in the coin box, and operate his calling device in accordance with the digits of the called subscriber's number.

The calling subscriber may first deposit a coin of suitable denomination in the coin collecting mechanism provided for that purpose. This mechanism is well understood and its operation need not be explained in detail. It will suffice to say that when the coin is deposited, it descends past the trigger mechanism which is released by the coin, with the result that the polarized magnet of the coin collecting mechanism is connected from the line conductor 11 to ground and the short circuit around the impulse springs of the calling device S is removed. The latter operation renders the calling de-

vice operative to control the central office switches. The coin may be deposited in the mechanism either before or after the receiver is removed. In any event, when the receiver is removed, a circuit is completed over the line conductors 11 and 12 in series for the relay 31 in the repeater D. The line relay 31, upon energizing, at armature 57 completes a circuit for the slow acting relay 32. Upon operating, the latter relay, at armature 60, prepares a circuit for the slow acting relay 35, at armature 61 completes a circuit for the polarizing winding of the electro-polarized relay 33, and at armature 59 places ground upon the private normal conductor 95, whereby the line of the substation A is rendered inaccessible to the connector switches, such as H. Another result of the energization of the line relay 31, is that at armature 58 a bridge is placed across conductors 97 and 98. This bridge may be traced from conductor 97 by way of armature 64 and its back contact, through the upper winding of the electro-polarized relay 33, through the winding of relay 34, and armature 58 and its front contact to conductor 98. The line relay 76 of the line switch C is energized over this bridge in series with the relay 34 of the repeater. Relay 34, upon operating, at armature 63 removes the short circuit around the impedance coil 36. The line relay 76 operates at armature 82 to close the circuit of the switching relay 75 in series with the motor magnet 77, and to connect the test wiper 84 to the above circuit at a point midway between the switching relay and the motor magnet at armature 81. The line switch C now operates in the usual manner to select an idle trunk line, which, it will be assumed, is the trunk line comprising conductors 90-92, inclusive. When the switch wipers 83-85, inclusive, of the line switch C are brought into engagement with the bank contacts 86-88, inclusive, associated with this trunk line, the switching relay 75, which has hitherto been short circuited, is energized. Upon operating, relay 75 at armature 79 places a ground potential upon the test contact 87 in order to busy the seized trunk line, at armatures 78 and 80 disconnects the conductors 97 and 98 from the windings of the line relay 76 and from ground, respectively, and at the front contacts of these armatures extends the said conductors over wipers 83 and 85, trunk conductors 90 and 92, and to the upper and lower windings of the line relay 100 of the first selector E.

Line relay 100, of the first selector is immediately energized over a circuit which includes the armature 58 and its front contact on the line relay 31 of the repeater D. Upon operating, relay 100 closes the circuit of the slow acting release relay 101. Upon

operating, relay 101 prepares the operating circuits of the selector E and places ground upon the release trunk conductor 91, thereby establishing the usual holding circuit for the switching relay 75 of the line switch C.

The calling subscriber at substation A may now operate his calling device in accordance with the first digit of the desired number. By this operation, a series of interruptions is produced in the circuit of the line relay 31 of the repeater D. The relay 31 operates in response to these interruptions, and at armature 58 repeats these interruptions to the line relay 100 of the selector E, and at armature 57 sends impulses of current through the winding of the slow acting relay 35. The latter relay operates at armature 64 to place a direct bridge across the conductors 97 and 98 through the armature 58 on the line relay. The relay 34 immediately deenergizes and at armature 63 short circuits the impedance coil 36. By these operations, the impulsing circuits are greatly improved.

The line relay 100 of the first selector E operates to control the vertical magnet of that switch in raising the wipers 103-105, inclusive, step by step until they are placed opposite the desired level of bank contacts. Shortly after the termination of the vertical movement of the switch, its trunk hunting movement begins and continues until the switch wipers are brought into engagement with the bank contacts associated with an idle trunk line, which, it will be assumed, are the bank contacts 110-112, inclusive. The switching relay 102 of the selector E is now energized and operates to extend the conductors 90 and 92 to the windings of the line relay 121 of the connector H.

The line relay 121 immediately operates to close the circuit of the slow acting release relay 122. The latter relay operates to prepare the impulsing circuits of the connector H at armature 139, and at armature 138 to place ground upon the release trunk conductor 164, thereby establishing a holding circuit for the selector E and line switch C.

The calling subscriber may now dial the next digit in the desired number. As before, a series of interruptions is produced in the circuit of the line relay 31 of the repeater D, and this relay operates to repeat this series to the line relay 121 of the connector H. The relays 34 and 35 operate as before to improve the impulsing circuits. The line relay 121 of the connector H, upon operating in response to these interruptions, sends a series of impulses to the vertical magnet 130. The circuit over which the first of these impulses is sent may be traced from ground by way of armature 137 and its back contact, armature 139 and its front contact, off normal springs 143 and

142, through the winding of the slow acting relay 123, and through the winding of the vertical magnet 130 to battery. Magnet 130 operates to raise the switch wipers 160-162, 5 inclusive, step by step until these wipers are brought opposite the proper level of bank contacts. Upon the first vertical movement of the switch, the off normal springs are operated, and the remaining vertical magnet 10 impulses traverse a new circuit, which is similar to the one above traced, except that it includes the off normal springs 143 and 144 and armature 140 on the slow acting relay 123, which is now energized. The slow 15 acting relay 123 is energized in series with the vertical magnet, and maintains its armature attracted throughout the vertical movement of the switch. Shortly after its termination, this relay deenergizes to transfer 20 the operating circuit to the rotary magnet 129.

When the calling device at the calling substation is operated in accordance with the next and final digit of the desired number, the line relay 31 of the repeater D operates in response to the interruptions produced in its circuit, and repeats these interruptions to the line relay of the connector H. This relay deenergizes a plurality of 25 times in response thereto, each time sending an impulse of current over the following circuit: ground, by way of armature 137 and its back contact, armature 139 and its front contact, off normal springs 143 and 30 144, armature 140 and its back contact, back contact and armature 149, armature 156 and its back contact, and through the winding of the rotary magnet 129 to battery. Magnet 129 operates to rotate the wipers 160-162, 35 inclusive, of the connector step by step until they are placed in engagement with the bank contacts 177-179, inclusive, associated with the line of substation A'. The slow 40 acting relay 126 is energized in multiple with the rotary magnet, and operates its armature 151 to connect the test wiper 161 to the test relay 125, and at armature 152 short circuits the contact springs comprising armature 149 and its back contact on the 45 test relay 125, so as to prevent the rotary magnet circuit being prematurely opened by energization of the test relay 125, while the switch wipers are being rotated past bank contact sets associated with busy telephone 50 lines.

Assuming that the desired line is busy, there will be a ground potential upon the test contact 178 and the test relay 125 will be energized. Upon operating, relay 125 at 55 armature 148 prepares a locking circuit for itself, which is closed upon the deenergization of the slow acting relay 126, at armature 149 opens the circuit of the rotary magnet, and at armature 150 connects a lead from the busy signalling machine to the

lower heavy talking conductors. By this operation, the calling subscriber is given a busy signal in order to inform him that the desired line is inaccessible for the present.

The calling subscriber will now replace 70 his receiver, thereby initiating the release of the operated switches and the refunding of the coin in the following manner: The replacement of the receiver at the calling substation opens the circuit of the line relay 31 75 in the repeater D, which deenergizes, opening the circuit of the slow acting relay 32 at armature 57, and at armature 58 opening the circuit of the line relay 121 of the connector H. After the deenergization of the 80 line relay 31 and before the deenergization of the slow acting relay 32, an impulse of current is sent to the slow acting relay 35. The latter relay, upon operating, at armature 66 prepares a circuit for the relay 29. 85 Upon the deenergization of the slow acting relay 32, the relay 29 is energized. Upon operating, relay 29 closes the circuit of the slow acting relay 28 at armature 53, and at armature 52 prepares a point in the circuit 90 extending from the battery B. Relay 28, upon operating, at armature 50 places ground upon the private normal conductor 95, so as to prevent the line of the substation A being connected with during the refunding operation. Other results of the energization of relay 28 are, that at armatures 49 and 51 a lead from the battery B is connected to line conductors 11 and 12 of the 95 substation A. The magnet in the paystation apparatus of the substation A is energized to operate its armature in such direction as to refund the coin deposited. Upon the deenergization of the slow acting 100 relay 35, which occurs shortly after the deenergization of the slow relay 32, the circuit of relay 29 is opened at armature 66. After a short interval relay 29 deenergizes 105 opening the circuit of the polarized magnet at the substation A and also the circuit of the slow acting relay 28. Relay 28 deenergizes to restore the normal battery and ground connections to the line conductors of the substation A and to remove ground from the private normal conductor 95 thereby 110 rendering the line of substation A idle. In this manner the circuits are returned to the normal condition. 115

The circuit of the line relay 121 of the connector H, being opened by the deenergization of the line relay 31 of the repeater D, causes this relay to deenergize, thereby opening the circuit of the slow acting relay 122. The latter relay deenergizes to remove ground from the release trunk conductor 125 164, and to close the circuit of the release magnet 128. Magnet 128 operates to restore the connector H to normal. The removal of ground from the release trunk conductor 164 opens the holding circuit of relays 130 102

and 75 in the selector E and line switch C, respectively. These relays deenergize to restore their respective switches to normal. In the above manner the connection is 5 released.

It will now be assumed that when the wipers 160-162, inclusive, of the connector H are rotated into engagement with the bank contacts 177-179, inclusive, the line of 10 the substation A' is idle. Under these conditions, no ground potential will exist upon the test contact 178, and the relay 125 will not be energized. Then, following the de- 15 energization of the slow acting relay 126, a circuit is completed which extends from ground on conductor 165 by way of armature 148 and its back contact, through the upper winding of the relay 127, back contact and armature 151, test wiper 161, test contact 178, through the winding of the switching relay 180 of the line switch C', and thence through the winding of the motor magnet 181 to battery. The relays 127 and 180 are energized over this circuit. Due to a 25 mechanical interlocking device controlled by the armature of the line relay 182, relay 180 does not completely attract its armatures, though it operates enough to disconnect the line of the called substation from its normal 30 battery and ground connections in the line switch C'.

In the connector H, the relay 127, upon operating, at armature 155 establishes a locking circuit for itself, at armature 154 connects direct ground to the test wiper 161, and at armatures 153 and 157 completes the signalling circuit. Ringing current from the generator is now intermittently applied to the called line until an answer is obtained.

40 When the called subscriber answers, a circuit is completed for the ring cut off relay 124 in the connector. Upon energizing, relay 124 establishes a locking circuit for itself at armature 146, at armature 145 and 147, 45 opens the ringing circuit, and at the front contacts of these armatures finally completes the talking connection. The back bridge relay 120 is immediately operated over the called line loop, and at armatures 135 and 136 reverses the connections of the line relay 121 with regard to the incoming trunk conductors, thereby causing a reversal of current in the windings of the relays 33 and 34 in the repeater D. The momentary de- 50 energization of relay 34 is without function. At this reversal the electro-polarized relay 33 is energized and operates at its armature 62 to close the circuit for the relay 30. Upon energizing, relay 30 establishes a locking circuit for itself at armature 56, and at armature 55 prepares a circuit so that when the calling subscriber hangs up, current from the battery B' will be supplied to the calling line in order to collect the deposited 55 coin.

The conversation may now take place between the calling and called subscribers, talking battery being supplied to the calling subscriber from the winding of the line relay 31, and the impedance coil 36 in the 70 repeater D and to the called subscriber from the windings of the back bridge relay 120 in the connector H. The talking circuit may be readily traced as it has been shown in the drawings by heavy lines. 75

Upon the termination of the conversation, both subscribers will replace their receivers upon their associated switch-hooks. By the replacement of the receiver at the calling substation, the release of the connection is 80 initiated in the same manner as before, the difference in this instance being that, as the relay 30 in the repeater D is energized, current from the battery B' is supplied to the line conductors of the calling line so that the 85 magnet of the paystation apparatus of substation A actuates its armature in such direction as to collect the coin deposited. It will be noted that the relay 30 is maintained energized over its locking circuit until the 90 connection is released. The switches C, E, and H are released in identically the same manner as was hereinbefore described.

Having described the operation of the repeater D and the paystation equipment at 95 substation A when the subscriber at this substation initiates a call, the manner in which this equipment operates when the subscriber is called by a toll operator will now be explained. For this purpose it will be assumed that an operator at the toll board desires to call the subscriber at substation A in order to complete a toll connection, which has been requested by that subscriber. The toll operator may have outgoing trunks at 100 her position terminating in line switches such as C, which have access to first selectors such as E by way of multiples such as the one shown terminating in bank contacts 97', 98', and 99. 110

Assuming that connection is established with bank contacts 97', 98', and 99 by the operation of the operator's line switch, in response to the first operation of the calling device, the selector E is caused to operate its 115 wipers to the proper level of bank contacts, and to then rotate them until they are brought into engagement with the bank contacts associated with an idle connector switch, which it will be assumed are the 120 bank contacts 110-112, inclusive. The switching relay 102 of the selector E immediately energizes to extend a connection to the line relay 121 of the connector H. The line relay 121 and the release relay 122 125 operates, as before, to prepare the switch circuits for operation.

In response to the two remaining digits of the called subscriber's number, the wipers 160-162, inclusive, are first raised vertically 130

to the proper level of bank contacts, and are then rotated until they are brought into engagement with the contacts 170-172, inclusive, in which is terminated the line of the 5 substation A. The operations so far described take place in the same manner as before.

Assuming that the line of the substation A is idle when the switch wipers of the connector H are brought into engagement with the bank contacts 170-172, inclusive, a circuit will be completed upon the deengagement of the slow acting relay 126, which extends from grounded conductor 165, armature 148 and its back contact, through the upper winding of relay 127, back contact and armature 151, test wiper 161, test contact 171, private normal conductor 95, armature 59 and its back contact in the repeater 10 D, normally closed springs, controlled by armature 50, and through the winding of the slow acting relay 27 to battery. The relay 27 is energized over this circuit, and, upon 15 operating, at armature 45 prepares another circuit for itself, at armature 46 closes the circuit of the slow acting relay 26, at armatures 44 and 48 disconnects the line of the substation A from its normal battery and ground connections in the repeater D, and 20 at armature 47 closes a circuit for the relay 30. Relay 26, upon operating, at armatures 41 and 43 prepares certain points in a testing circuit as will appear later, and completes the circuit of the slow acting relay 29 25 at armature 42. Relay 30, upon operating, at armature 55 prepares a certain point in the coin collecting circuits, and at armature 56 prepares a locking circuit for itself. Relay 29, upon operating, at armature 54 closes 30 a locking circuit for relay 30, at armature 53 closes a circuit for the relay 28, and prepares another point in the coin controlling circuits at armature 52. Upon operating, relay 28, at armature 50, transfers the connection 35 from the private normal conductor from its normally closed springs to the said armature, and at armatures 49 and 51 closes another point in the above mentioned testing circuit.

50 In the connector H, relay 127, upon operating, establishes a locking circuit for itself and completes the ringing circuit. The subscriber at substation A is now intermittently signalled until he answers.

55 When the receiver is removed, the ring cut off relay 124 is energized to disconnect the ringing current. The back bridge relay 120 is energized and operates to reverse the current flow over the incoming trunk conductors. By this reversal the operator at the toll board is given the usual supervisory signal to notify her that the called subscriber has answered.

60 The toll operator will now come in on the line by throwing her listening key and after

ascertaining the proper party is at the telephone, will request him to deposit the required amount in the coin box. By the usual audible signal the operator is informed when the correct amount is placed in the 70 coin chute and will complete the connection. From this point on the operations may take either of two courses.

Should the connection not be properly completed at the present time, the toll operator will wish to refund the coins deposited in the paystation mechanism. To accomplish this result, the toll operator will request the calling subscriber to leave his receiver off the hook until the coins are refunded and to then replace it. The operator will now release the connection. The release of the operated switches E and H takes place in the same manner as has been 85 before described.

By the release of the connector H, ground is removed from the private normal conductor 95, whereby the circuit of the slow acting relay 27 in the repeater D is opened. After 90 a short interval, this relay deenergizes, thereby opening the circuit of the slow acting relay 26 at armature 46 and the original energizing circuit of the relay 30 at armature 47. Other results of the deenergization of 95 relay 27 are that at armature 45 ground is connected to the private normal conductor 95, in order to busy the line of the substation A during the coin controlling operations, and at armatures 44 and 48 the relay 25 is connected to the line conductors 11 and 12, 100 thereby completing the above mentioned testing circuit. As the receiver is off at the substation A, relay 25 immediately energizes to open the circuit of the relay 30. Relay 30 at once deenergizes to prepare a point in the coin refunding circuits. Upon the deenergization of the slow acting relay 26, current from the battery B is applied to line conductors 11 and 12, in order to actuate 105 the magnet at the substation A in such manner that the deposited coins are refunded to the subscriber thereat. Upon the deenergization of the relays 35, 29, and 28, the circuits of the repeater D are restored to normal as before.

110 It will now be assumed that in the preceding toll connection the toll operator desires to collect the coins deposited at substation A. In order to do this, the toll operator merely has to refrain from pulling down the connection until the subscriber at substation A hangs up. By the usual supervisory signal the operator will know when 120 this is done and she will then release the connection extending to the substation A. The operation of the various relays in the repeater D is similar to their operation in the preceding connection, the only difference being that, as the receiver is on the hook 125 at the substation A, the relay 25 in the 130

- repeater D will not be energized to open the circuit of the relay 30. As the relay 30 remains energized, current from the battery 'B' is supplied to the line conductors 5 11 and 12 of the calling substation to actuate the magnet thereof to collect the deposited coins rather than to refund them. The apparatus is released in the usual manner.
- 10 It will be understood, of course, that the repeater D can be used advantageously for paystation lines even when a toll service trunking system is employed if there are only a small number of these lines making 15 it undesirable to equip the toll service trunks with coil controlling apparatus.

The features of the invention having been described and ascertained, what is considered to be new and desired to have protected 20 by Letters Patent will be pointed out in the appended claim.

What I claim is:

1. In a telephone system, an automatic switch, a called line, means for operating 25 said switch to connect with said line, means for releasing said switch, paystation mechanism on said line, a magnet in said paystation mechanism for controlling deposited coins, and means individual to said line 30 operative when said automatic switch is released for closing a circuit for energizing said magnet.
2. In a telephone system, an automatic switch, a called line, means for operating 35 said switch to connect with said line, means for releasing said switch, paystation mechanism at the substation on said line, a magnet in said paystation mechanism for controlling deposited coins, and relay means individual 40 to said line operative responsive to said release for projecting current out on said line to energize said magnet.

3. In a telephone system, an automatic switch, a line, paystation mechanism at the 45 substation on said line, a magnet in said paystation mechanism for controlling coins deposited therein, a repeater for said line, a high voltage battery, means on operating said switch to connect with said line, means 50 for releasing said switch, and relays in said repeater operative responsive to such release to apply said high voltage battery to said line to energize said magnet.

4. In a telephone system, an automatic 55 switch, a line, paystation mechanism at the substation on said line, means for operating said switch to connect with said line, means for releasing said switch either before or after the receiver is replaced at said substation, means operative if said release occurs after said receiver is replaced for collecting coins deposited in said mechanism, and means operative if said release occurs before 60 said receiver is replaced for refunding said coins.

5. In a telephone system, an automatic switch, a line, paystation mechanism at the substation on said line, a magnet in said mechanism for collecting or refunding coins deposited therein, high voltage batteries of 70 opposite polarity, a repeater individual to said line, means for operating said switch to connect with said line, means for releasing said switch, relays in said repeater operative if said release occurs before the receiver is replaced at the substation on said line for connecting one of said high voltage batteries to said line to energize said magnet to refund deposited coins, said relays operative if said release occurs after said receiver 80 is replaced to connect the other of said batteries to said line to energize said magnet to collect said coins.

6. In a telephone system, a first line, paystation mechanism at the substation on said line, a magnet in said mechanism for controlling deposited coins, a repeater individual to said line, a second line, means including automatic switches controlled from said first line for extending a connection to 90 said second line, means for releasing said connection, relay controlled means in said repeater operative responsive to such release to energize said magnet, means for completing a connection to said first line, and means for releasing said second completed connection, said relay controlled means in said repeater also operating responsive to said last release to energize said magnet.

7. In a telephone system, a line, paystation mechanism at the substation on said line, a magnet in said mechanism for controlling deposited coins, means for extending a connection to said line or from said line to another line, means for releasing 105 either connection, and relay equipment individual to said line operative in event of either release to cause the actuation of said magnet.

8. In a telephone system, a line, paystation mechanism therefor, means for extending a connection either to or from said line, means for releasing said connection, means responsive to the release of a connection extending from the line for either collecting or refunding coins deposited in said mechanism depending upon whether the call was answered or not, and means responsive to the release of a connection extending to the line for either collecting or refunding coins deposited in said mechanism depending upon whether the subscriber on said line restores his receiver before or after the connection is released.

9. In a telephone system, a pair of lines, an automatic switch for extending a connection between said lines, paystation mechanism on one of said lines, means for releasing said switch either before or after the subscriber on said paystation line has hung 130

up his receiver, and means responsive to the release of said switch for either collecting or refunding the coins deposited in said mechanism depending on whether or not the 5 said subscriber has hung up.

10. In a telephone system, an automatic switch, a line, paystation mechanism at the substation on said line, means for operating said switch to connect with said line, means 10 for releasing said switch either before or after the receiver is replaced at said substation, and means rendered operative by the replacement of the receiver before the switch is released for causing the coins deposited 15 in said mechanism to be collected responsive to the release of said switch.

11. In a telephone system, an automatic switch, a line, paystation mechanism at the substation on said line, means for operating 20 said switch to connect with said line, means for releasing said switch either before or after the receiver is replaced at said substation, means for collecting coins deposited in said mechanism, means for refunding coins 25 deposited in said mechanism, means rendered effective by the replacement of the receiver before the switch is released for rendering said collecting means operative responsive to the release of said switch, and 30 means operative responsive to the release of said switch before the receiver is replaced to cause said coin refunding means to function.

12. In a telephone system, a line paystation mechanism therefor, an automatic 35 switch operated to seize said line, means for releasing said switch either before or after the subscriber hangs up his receiver, and means responsive to the release of said switch for collecting the coins deposited in said 40 mechanism if the switch is released after the subscriber hangs up his receiver.

13. In a telephone system, a line, paystation mechanism therefor, an automatic switch operated to seize said line, means for 45 releasing said switch either before or after the subscriber hangs up his receiver, means responsive to the release of said switch for refunding the coins deposited in said mechanism if the switch is released before the 50 subscriber hangs up his receiver, and means responsive to the release of said switch for collecting the coins deposited in said mechanism if the switch is released after the subscriber hangs up his receiver.

55. 14. In a telephone system, a line, paystation mechanism therefor, an automatic switch operated to seize said line, means for releasing said switch either before or after the subscriber hangs up his receiver, and 60 means responsive to the release of said switch for refunding the coins deposited in said mechanism if the switch is released before the subscriber hangs up his receiver.

15. In a telephone system, a telephone line 65 provided with paystation mechanism, means

for extending a connection to said line, means for releasing said connection, and relay means individual to said line and responsive to said release for controlling said mechanism to either collect or refund deposited coins. 70

16. In a telephone system, a telephone line provided with paystation mechanism, means for extending a connection to said line, 75 means for releasing said connection, and relay means individual to said line and responsive to said release for controlling said mechanism to either collect or refund deposited coins depending upon whether the subscriber on said line restores his receiver before or after the connection is released. 80

17. In a telephone system, a telephone line provided with paystation mechanism, means for extending a connection to said line, 85 means for releasing said connection, and relay means individual to said line and responsive to said release for controlling said mechanism to either collect or refund deposited coins depending upon a switching operation performed by the subscriber on said line before or after the connection is released. 90

18. In a telephone system, a line provided 95 with paystation mechanism, means for extending a connection to said line, means at said line for performing a switching operation, a test relay individual to said line and responsive to said switching operation, means for releasing said connection and means controlled by said test relay upon 100 release of said connection for operating said mechanism to either collect or refund deposited coins. 100

19. In a telephone system, a line provided 105 with paystation mechanism, means for extending a connection to said line, means at said line for performing a switching operation, a test relay individual to said line and responsive to said switching operation, means for releasing said connection, and means controlled by said test relay upon 110 release of said connection for operating said mechanism to either collect or refund deposited coins depending upon the time said switching operation occurs relative to the release of said connection. 115

20. In a telephone system, a line provided 120 with paystation mechanism, means for extending a connection to said line, a test relay individual to said line, means for releasing said connection, means at said line for performing a switching operation prior to said release, and means operable upon said release and controlled by said test relay 125 cooperating with said switching operation for actuating said mechanism to collect deposited coins.

21. In a telephone system, a line provided 130 with paystation mechanism, means for extending a connection to said line, a test re-

lay individual to said line, means for releasing said connection, and means controlled by said test relay upon release for actuating said mechanism to refund deposited coins.

22. In a telephone system, a line provided with paystation mechanism, means for extending a talking connection to said line, a test relay individual to said line, means controlled from the calling station for releasing said connection, and means responsive to said release and controlled by said test relay for actuating said mechanism to refund deposited coins.

15 23. In a telephone system, a line provided with paystation mechanism, means for extending a talking connection to said line, a test relay individual to said line, means controlled from the calling station for releasing said connection, means at said line for performing a switching operation, and means

responsive to said release and controlled by said test relay for actuating said mechanism to collect deposited coins if said switching operation is performed prior to said release. 25

24. In a telephone system, a line provided with paystation mechanism, means for extending a talking connection to said line, a test relay individual to said line, means controlled from the calling station for releasing said connection, means at said line for performing a switching operation, and means responsive to said release and controlled by said test relay for actuating said mechanism to collect deposited coins if said switching 30 operation is performed prior to said release and to refund deposited coins if said switching operation is performed after release. 35

In witness whereof, I hereunto subscribe my name this 30th day of June, A.D., 1922.

JOHN WICKS.
